(57) **CLAIM**

The ornamental design for a solar panel sunshade, as shown and described.

DESCRIPTION

FIG. 1 is a perspective front view of the solar panel sunshade; FIG. 2 is a front elevation view of the solar panel sunshade; FIG. 3 is a rear elevation view of the solar panel sunshade; FIG. 4 is a left side elevation view of the solar panel sunshade; the right side view being a mirror image thereof; and, FIG. 5 is a top view of the solar panel sunshade; the bottom view being a mirror image thereof. The windshield is shown in broken lines for illustrative purposes only and forms no part of the claimed design.
